RAILROAD-GATE.

1,034,701.

Specification of Letters Patent.

Patented Aug. 6, 1912.

Application filed November 27, 1911. Serial No. 662,562.

To all whom it may concern:

Be it known that we, WYATT A. FLEMING and BYRON ANDERSON, citizens of the United States, residing at Adkins, in the 5 county of Bexar and State of Texas, have invented certain new and useful Improvements in Railroad-Gates, of which the following is a specification.

Our invention relates to new and useful 10 improvements in automatic railway gates. Its object is to provide a railway gate adapted to be correlated with two tracks at their intersection, and adapted to be automatically swung into a position transverse with 15 one of said tracks when a train approaches along the other.

Another object is to provide a mechanism 20 for operating the gate by triggers normally projecting slightly above the rail, one of which triggers will be pressed down by the wheels of a train approaching the crossing from any direction.

Finally the object of our invention is to 25 provide a device of the character described that will be strong, durable, simple, and efficient and comparatively easy to construct, and also one the various parts of which will not be likely to get out of working order.

30 With these and various other objects in view, our invention has relation to certain novel features of the construction and operation, an example of which is described in the following specification and illustrated 35 in the accompanying drawing, wherein:—

Figure 1 is a plan view of a railroad crossing, showing the herein described automatic gate associated therewith. Fig. 2 is a view of the same in side elevation, a pair 40 of car wheels being shown acting upon one of the triggers, causing the gate to assume a position parallel with the track upon which said wheels are mounted. Fig. 3 is a perspective view of a construction comprising 45 the gate support and a mechanism correlated with the gate to swing the same through 90 degrees. Fig. 4 is a detail perspective view showing one of the operating triggers, which are employed to swing the 50 gate when a train approaches the same.

Referring now more particularly to the drawing, wherein like numerals of reference 55 designate similar parts in all the figures the numerals 1 and 2 respectively denote two tracks intersecting each other at right angles, the gate constituting the present in-

vention being correlated with the crossing thus formed. The gate proper consists of a horizontal bar 3, pivoted near one of its extremities upon the top of a post 4, and adapted to be swung through a quarter circle, the gate being transverse of the tracks in its limiting positions. The post 4 is stationary and rigid and is spaced a sufficient distance from both tracks to eliminate any 60 possibility of its being struck by passing trains. In order to decrease the friction between the gate and its pivot when the former is swung, a brace 5 is furnished as an additional supporting means for the 65 gate, said brace preferably having the form of a quarter circle with one extremity attached to the bar 3 some distance from its pivot and the other extremity supported by a pin 6, projecting from the middle portion of the post and turned upwardly. The 70 connections between the brace 5 and the parts 3 and 4 will be sufficiently loose to permit the gate to swing freely between its limiting positions transverse of the two 75 tracks. The gate will preferably be mounted at an elevation several feet above the tracks and will have a length such that its extremity will project a short distance beyond the tracks in the limiting positions. 80 When the gate is being swung in either direction, it will contact with a vertical post 7 upon reaching its limiting position transverse of the track to be closed by the gate. Each post 7 is reinforced by an inclined 85 brace 8, upon the side opposite to that with which the bar 3 contacts. The direct means by which the gate is swung consists in a semi-circular plate 9 pivotally mounted upon the upper portion of the post 4, its 90 pivotal axis being such as to form 45 degree angles with the directions of the two tracks. From the middle portion of the curved edge of this plate two pins 10 project engaging the bar 3 at each side thereof. Owing to 95 this construction it is apparent that a swinging motion of the gate about its vertical pivot will result when the plate 9 is subjected to any rotation about its horizontal axis. The plate 9 and the bar 3 are so related that when the diametrical edge of the former is in a horizontal position, the latter 100 will be midway between its limiting positions, or will form a 45 degree angle with both tracks. 105

A description will now be given of the mechanism employed to subject the plate 9

to a partial rotation, when a train approaches the crossing from any direction. A rock shaft 11 is mounted parallel and adjacent to each track, said shaft being received by bearings 12 carried by the rail-tie extremities. The shafts 11 pass between the post 4 and the tracks, and each shaft will preferably be extended a considerable distance beyond the crossing in both directions. In crossing the tracks, the shafts 11 may be passed through the flanges of the rails, said flanges acting as bearings for the shafts. At points adjacent to the posts 4, each shaft 11 is provided with a U shaped crank 13, and each crank is connected through a pitman 14 with the plate 9, the pitmen being attached to said plate adjacent to the intersections of its circular and straight edges. The two extremities of each rock shaft 11 are provided with parallel crank arms 15, each of which arms has pivotal connection with a lug 16 provided upon the free extremity of a trigger 17, pivoted adjacent to the rail. The relation between the various parts of the mechanism is such that the triggers adjacent to the rail of either track will project slightly above the ball of said rail when the bar 3 is transverse with the track of which said rail forms a part. Thus when a train approaches a crossing from any direction it will automatically throw the gate clear of its track, through the pressure of its wheels upon one of the triggers 17, causing the gate to occupy a position transverse of the other track, thus signaling any train approaching upon the other track to stop.

In case two trains are approaching the crossing upon different tracks, this device very much reduces the possibility of a collision between said trains by automatically signaling one of them to stop or slow up until the other passes. The rock shaft 11 may be sufficiently extended in both directions to produce an operation of the gate one or two minutes before the train reaches the crossing so that any train approaching upon the other track will have time to slow up if necessary. For the sake of clearness no boxing has been shown to partially in-

close the triggers, but it is to be understood that such may be employed to prevent stones or other impediments preventing the triggers from operating.

It is apparent that various changes and modifications may be made in the above described device without departing from the spirit or sacrificing the advantages thereof, and the invention is therefore presented as including all such changes and modifications as come within the scope of the following claim.

What we claim is:—

An automatic railway gate comprising a horizontal bar correlated with a railway crossing and spaced above the same, said bar being adapted to swing through a quarter circle and being transverse of the tracks in its limiting position, a semi-circular plate pivotally mounted beneath said bar adjacent to the pivoted end thereof, and having its axis forming angles of 45 degrees with the directions of the tracks, pins provided upon the circular edge of said plate at the middle portion thereof adapted to engage the bar respectively at its two sides; a rock shaft mounted adjacent to each track of the crossing; a U shaped crank in each shaft substantially beneath said plate; a pair of pitmen having their lower ends attached to said cranks and their upper ends attached to said plate at the intersections of its circular and diametrical edges, crank arms carried by the extremities of the rock shafts, and pivoted triggers having their free ends engaged by said crank arms each located adjacent to a track rail and projecting above the ball of said rail when the gate is transverse of the track of which said rail forms a part.

In testimony whereof we have signed our names to this specification in the presence of two subscribing witnesses.

WYATT A. FLEMING.
BYRON ANDERSON.
